(57) **CLAIM**

The ornamental design for a frame for localization system, as shown and described.

DESCRIPTION

FIG. 1 is a front view of a frame for localization system showing the claimed design;

FIG. 2 is a rear view thereof;

FIG. 3 is a left side view thereof;

FIG. 4 is a right side view thereof;

FIG. 5 is a bottom view thereof;

FIG. 6 is a top view thereof;

FIG. 7 is a top front perspective view thereof;

FIG. 8 is a bottom front perspective view thereof;

FIG. 9 is a top rear perspective view thereof; and,

FIG. 10 is a bottom rear perspective view thereof.

The broken lines, the areas within them and the areas surrounded by both broken lines and solid lines depict portions of the tracker assembly for localization system that form no part of the claimed design.
